Hamilton-Skotch Corporation, Hamilton, Ohio, a cor-
poration of Ohio

Filed Jan. 22, 1963, Ser. No. 73,278

Term of patent 14 years

(Cl. D58—17)

Fig. 1.

Fig. 2.

FIG. 1 is a front elevational view of an insulated jug, showing my new design;

FIG. 2 is a side elevational view thereof;

FIG. 3 is a top plan view thereof; and

FIG. 4 is a bottom plan view thereof.

The rear and side of the insulated jug not shown are substantially the same as the front and side thereof shown in FIGS. 1 and 2.

I claim:

The ornamental design for an insulated jug, substantially as shown and described.
